UNITED STATES PATENT OFFICE.

ARTHUR BRUNE AND CHARLES H. STONE, OF COLEYVILLE, TEXAS.

COTTON-CLEANING MACHINE.

1,303,160.

Specification of Letters Patent.

Patented May 6, 1919.

Application filed May 11, 1917. Serial No. 167,960.

To all whom it may concern:

Be it known that we, ARTHUR BRUNE and CHARLES H. STONE, citizens of the United States, and residents of Coleyville, in the 5 county of Cottle and State of Texas, have invented certain new and useful Improvements in Cotton-Cleaning Machines, of which the following is a specification.

This invention relates to new and useful 10 improvements in machines for cleaning cotton, and the primary object of the invention is to provide a device of this character that includes in a single casing, means for cleaning bolly and seed cotton and separating 15 the lint therefrom, and a suction operated draft outlet for drawing the clean cotton from the machine, and feeding the same to the gin stand.

Another object of the invention is to provide 20 a cotton cleaning machine of this character provided with a suction control outlet, that has a branch associated therewith, to draw the lint from the cotton during the cleaning operation.

A still further object of the invention is 25 to provide a device of this character which is easily and simply constructed, inexpensive to manufacture, and one which will be very efficient in operation.

With these and numerous other objects in 30 view our invention consists of the novel features of construction, combination and arrangement of parts which will be herein-referred to and more particularly pointed 35 out in the specification and claim.

In the accompanying drawings:

Figure 1 is a side elevation of the machine;

Fig. 2 is a vertical longitudinal section 40 through the same, and

Fig. 3 is a top plan detailed view of a portion of the movable comb that is associated with the cleaning means.

In describing our invention we shall refer 45 to the drawings in which similar reference characters designate corresponding parts throughout the several views. The numeral 1 designates a supporting frame of our machine, which comprises a plurality of up- 50 right standards having a main supporting frame 2 carried thereby, which supports the main portion 3 of the casing, which has the beating means for the cotton contained therein. The casing which forms a cover 55 for the whole machine is divided into two parts, the parts 3 containing the beating

means, while the part designated by the numeral 4 contains the cotton separating means. The inlet for the machine designated 5 is through the end portion 3 of the 60 casing, while the outlet 6 is connected with the separating means in the portion 4 of said casing.

The portion 3 of the casing contains a 65 pair of cylindrical beaters 7 mounted on horizontally extending axes 8 extending through the sides of the casing, and mounted on the frame 2. These beaters are revolved by any desired means, the same being adapted to be rotatably connected, as 70 also is a rotatably mounted conveyer 9 disposed adjacent the rear of said beaters. Directly within the inlet 5 of the machine, is a guide member 10, that directs the cotton drawn therein downwardly against the first 75 of the beaters 7. Adjustably mounted within said portion 3, and co-operatively related with the beaters 7 is a comb 11, provided with a projecting handle 12, that permits the adjustment of the same, said comb comprising a plurality of stationary teeth which, as have been stated are co-operatively related with the projecting teeth 13 on the beater. This will carry the cotton there-through, and tend to remove the heavier 80 particles of dirt from the same, and as said cotton is carried by the teeth on the beater through the machine, it passes over arcuate screens 14 positioned beneath beaters, and owing to the action to which said cotton is 85 subjected the dirt, etc., will be shaken therefrom and dropped into a receptacle 15 that is positioned beneath said screens. The receptacle 15 is provided with an outlet door 90 95 16, whereby the dirt may be removed therefrom when the receptacle is filled.

As the cotton passes from the rear beater 7, it will be engaged by the rotatably mounted conveyer 9, which comprises a plurality of radially projecting blades 17 mounted on 100 a horizontally extending axis, said blades having their outer ends connected by rubber strips 18, which will gather the cotton and pass the same therethrough and into the portion 4 of the casing, as clearly shown in 105 Fig. 2 of the drawings.

The portion 4 of the casing in which is positioned the cotton separating means has mounted therein a pair of rotatably mounted disintegrating rolls 19, which have disposed adjacent thereto three picker wheels 20, which are co-operatively related there-

with, one picker wheel being disposed adjacent one of the disintegrating rolls, while a pair of picker wheels are disposed adjacent the opposite roll. The picker wheels and 5 saws are disposed in vertical alinement, and guide means 21 are associated therewith, to direct the passage of cotton therethrough. After the burs have been removed from the cotton through the operation of the rolls 10 and picker wheels, the same drop to the bottom of the guide portions 21, and pass through an outlet 22 in the bottom thereof. The cotton will be carried by the rolls into engagement with a brush 22', that is also 15 rotatably mounted through the portion 4, and hence to the outlet 6, that is provided with suction operated means associated therewith, to readily draw the cotton therefrom and carry it through the pipe 23 to the 20 stand.

A branch pipe 24 is connected with the suction control outlet 6, said branch extending forwardly and along the top of the portion 3 of the casing, and having its forward 25 end communicating therewith, said communicating portion having a wire screen 25 positioned therein, as clearly shown in Fig. 2 of the drawings. This is disposed directly over the cotton beating means within the 30 portion 3 of the casing, and as the cotton is subjected to the action of the beaters, it is obvious that lint, etc., will rise therefrom, and as the suction operated means is connected with the pipe 24, said lint will be 35 drawn therethrough, and through the outlet pipe 23. This affords an easily and simply constructed mechanism for withdrawing the lint from the cotton, without wasting the same.

40 In operation when the cotton is fed through the inlet 5 to the portion 3 of the casing, the same will be subjected to the action of the beaters 7, which will thoroughly cleanse the same, and remove all loose dirt 45 therefrom, said dirt dropping through the screens 14 into the receptacle 15. The cotton is passed by the rotatably mounted beaters to the conveyer 17, and thence carried by the same downwardly and dropped into the portion 4 of said casing. Within this portion, the cotton is subjected to the separating operation, and the burs and trash are removed therefrom by the coöperation of the rolls and picker wheels. After the cotton 50 has been separated, the same is carried over the brush 22', and out through the suction

control outlet 6. The branch pipe 24 which is connected with the cleaning means, will remove lint from the cotton and also carry the same to the outlet. 60

The various beaters, and rotatably mounted rolls, picker wheels, brush and conveyer are adapted to be connected by a chain gearing, or any other desired type, not shown, and all of the same operated by a single 65 motor. However this is optional, and any desired means may be employed for rotating these parts. The operation of this device is automatic, as when the cotton is fed to the machine, it is carried therethrough, and to 70 the stand in a manner hereinbefore fully described. The beating and separating operations are efficiently carried out, and the cotton will be thoroughly cleaned when drawn into the outlet 6, where it is carried to the 75 gin stand.

From the foregoing description, taken in connection with the accompanying drawing, the advantages of the construction, and of the method of operation will be readily apparent to those skilled in the art to which the invention appertains, and while we have described the principle of operation of the invention, together with the device which we now consider to be the best embodiment 85 thereof, we desire to have it understood that the device shown is merely illustrative, and that such changes may be made when desired as are within the scope of the claim appended hereto. 90

Having fully described our invention, what we claim as new, and desire to secure by Letters Patent is:

A cotton cleaning machine comprising a casing, a plurality of horizontally arranged 95 rotatable beaters therein over which the cotton is adapted to pass, rotatable picker wheels arranged in the casing beyond said beaters, disintegrating rolls positioned in proximity to said picker wheels, a secondary 100 housing receiving the picker wheels and disintegrating rolls, and a pneumatic conveyer having a substantially V-shaped branch extending into the casing, one extremity of the branch communicating with the secondary 105 casing and the other extremity thereof communicating with that portion of the casing of the beaters.

In testimony whereof, we affix our signatures hereto.

ARTHUR BRUNE.
CHARLES H. STONE.
